(57) **CLAIM**

The ornamental design for a dispenser for personal care composition, as shown and described above.

DESCRIPTION

The patent or application file contains at least one drawing executed in color. Copies of this patent or patent application publication with color drawing(s) will be provided by the Office upon request and payment of the necessary fee.

FIG. 1 is a perspective view of a dispenser for personal care composition in closed position;

FIG. 2 is a front view thereof;

FIG. 3 is a top plan view thereof;

FIG. 4 is a bottom view thereof;

FIG. 5 is a perspective view thereof in open position;

FIG. 6 is a front view of FIG. 5;

FIG. 7 is a top plan view of FIG. 5.

FIG. 8 is a perspective view of a dispenser for personal care composition in closed position;

FIG. 9 is a front view thereof;

FIG. 10 is a top plan view thereof;

FIG. 11 is a bottom view thereof;

FIG. 12 is a perspective view thereof in open position;

FIG. 13 is a front view of FIG. 12;

FIG. 14 is a top plan view of FIG. 12.

FIG. 15 is a perspective view of a dispenser for personal care composition in closed position;

FIG. 16 is a front view thereof;

FIG. 17 is a top plan view thereof;

FIG. 18 is a bottom view thereof;

FIG. 19 is a perspective view thereof in open position;

FIG. 20 is a front view of FIG. 19;

FIG. 21 is a top plan view of FIG. 19.

FIG. 22 is a perspective view of a dispenser for personal care composition in closed position;

FIG. 23 is a front view thereof;

FIG. 24 is a top plan view thereof;

FIG. 25 is a bottom view thereof;

FIG. 26 is a perspective view thereof in open position;

(Continued)

FIG. 27 is a front view of FIG. 26;
 FIG. 28 is a top plan view of FIG. 26.
 FIG. 29 is a perspective view of a dispenser for personal care composition in closed position;
 FIG. 30 is a front view thereof;
 FIG. 31 is a top plan view thereof;
 FIG. 32 is a bottom view thereof;
 FIG. 33 is a perspective view thereof in open position;
 FIG. 34 is a front view of FIG. 33;
 FIG. 35 is a top plan view of FIG. 33.
 FIG. 36 is a perspective view of a dispenser for personal care composition in closed position;
 FIG. 37 is a front view thereof;
 FIG. 38 is a top plan view thereof;
 FIG. 39 is a bottom view thereof;
 FIG. 40 is a perspective view thereof in open position;
 FIG. 41 is a front view of FIG. 40;
 FIG. 42 is a top plan view of FIG. 40;
 FIG. 43 is a perspective view of a dispenser for personal care composition in closed position;
 FIG. 44 is a front view thereof;
 FIG. 45 is a top plan view thereof;
 FIG. 46 is a bottom view thereof;
 FIG. 47 is a perspective view thereof in open position;
 FIG. 48 is a front view of FIG. 47;
 FIG. 49 is a top plan view of FIG. 47.
 FIG. 50 is a perspective view of a dispenser for personal care composition in closed position;
 FIG. 51 is a front view thereof;
 FIG. 52 is a top plan view thereof;
 FIG. 53 is a bottom view thereof;
 FIG. 54 is a perspective view thereof in open position;
 FIG. 55 is a front view of FIG. 54;
 FIG. 56 is a top plan view of FIG. 54.
 FIG. 57 is a perspective view of a dispenser for personal care composition in closed position;
 FIG. 58 is a front view thereof;
 FIG. 59 is a top plan view thereof;
 FIG. 60 is a bottom view thereof;
 FIG. 61 is a perspective view thereof in open position;
 FIG. 62 is a front view of FIG. 61; and,
 FIG. 63 is a top plan view of FIG. 61.
